UNITED STATES PATENT OFFICE.

WILLIAM P. DALRYMPLE, OF CHICAGO, ILLINOIS.

SEMAPHORIC INDICATOR.

Application filed November 12, 1926. Serial No. 147,957.

This invention relates to improvements in indicators and more especially to the semaphoric type of thermal indicator used on automobile radiator caps to give an indication 5 of the temperature of the engine cooling fluid; and consists essentially in certain improvements in the construction and mounting of the semaphore arm and in the application of the actuating arm to the semaphore.

10 This invention relates more particularly to the type of semaphore radiator indicator in which the semaphore is centrally pivoted to the instrument frame and engaged near the axis by the arm of the thermal element, so 15 that the semaphore is swung back and forth by the thermal responsive movement of said arm.

Heretofore a frame plate was secured in the instrument frame with a portion of the 20 metal extruded from one side to provide a stud; and the semaphore arm plate was inserted between the end of a leaf spring or retainer strap, which was secured at one end to the frame plate, with the stud projecting 25 through a small hole in the semaphore arm plate. A triangular aperture was cut in the arm plate leaving a bar at the edge. The actuating arm of the instrument was then notched at the side to receive the bar, so that 30 the end could be engaged in the apex of the triangular aperture. Since the retainer can press only lightly against the semaphore plate on account of the friction, the result was that the plate was not securely held on the stud, 35 and was easily dislodged from position. The bar rubbed on the actuating arm, and the notch weakened the arm and made it difficult to adjust the device to operate at the desired temperatures; since the adjustment is necessarily accomplished by bending the arm. The 40 parts were difficult to assemble and the design was not well adapted for obtaining accurate instruments by the methods of quantity production.

45 Accordingly, in this invention an improved mounting is provided for the semaphore arm plate by locking the movable end of the retaining leaf down after the semaphore arm is inserted in position; and a construction is 50 provided wherein notching the actuating arm is eliminated; the main objects being to provide a device which can be assembled on a quantity basis and accurate instruments produced; to provide such a device in which the 55 different parts may be mechanically adjusted before parts are assembled; to provide an

instrument in which the parts cannot be dislocated by such jolting and vibrating as is encountered in use on an automobile; to provide an instrument which operates with very 60 little friction and offers very little resistance to the movement of the responsive actuating member.

An illustrative embodiment of this invention is shown in the accompanying drawing 65 in which:

Figure 1 is an elevation of a semaphore automobile radiator instrument.

Fig. 2 is a section on an enlarged scale 70 taken on line 2-2 of Fig. 1.

Fig. 3 shows the support plate and retainer arm assembled thereon.

Fig. 4 is a side elevation of Fig. 3.

Fig. 5 is an enlarged section taken on the 75 line 5-5 of Fig. 3.

Referring to the drawings, the instrument frame comprises a housing 1 having an opening 2 therethrough in which the semaphore 3 is mounted, and a hollow threaded stem 4, integral with the housing 1, which threads 80 into the radiator cap. A cup 5 is inserted in the stem 4, in a well known manner and contains a thermal element to which the control arm 6 is attached and is thereby made movably responsive to the changes in the temperature of the radiator. When the radiator is cold, the upper end of the arm 6 is to the left as shown, and when the temperature rises, the end of the finger moves to the right and rotates the semaphore arm 3 counter-clockwise to the opposite position.

The support plate 7 is received in suitable recesses provided in the central flange 8 of the housing 1, and is held in position by means of the glass retaining ring 9 which is forced into the angular recess 10 in the base of the housing 1. The plate 7 has a depending portion 11 from which is excluded a projection or stud 12, which is located in the center of the housing 1. A thin leaf spring retainer 13 is anchored at one end of the plate 7 by means of stakes 14, stamped out of the leaf spring 13, which are inserted in the counterbored hole 15 in the upper portion of the plate 7, and bent over as shown. The free end of the leaf spring 13 is apertured 100 to fit over the stud 12 and is convoluted to provide a line contact.

The semaphore 3 comprises a bi-lobular stamping having an aperture 16 at the center, 110 with a radial, outwardly opening V-notch 17 directly below the aperture 16. The sema-

phore arm 3 is inserted between the free end of the leaf 13 and the plate 7 with the lug 12 projecting through the aperture 16. For locking the retainer member 13 after the 5 semaphore 3 is in position, a tongue 18 is bent out from the main portion of the leaf 13 and projects through a receiving aperture 20 in the plate 7. After the semaphore arm is in position, the projecting end of the tongue 10 18 is bent over as shown more plainly in Fig. 5. The tongue 18 is bent over loosely so as to not increase the pressure on the plate 3, but to limit the upward movement of the end of the leaf 13, so that the semaphore arm cannot be displaced from the stud. 15

The arm 6 projects into the notch 17, and the end engages between two oppositely arranged shoulders 21, at the apex of the notch and close to the rotational axis of the arm 3. 20 Projections 22 are also provided at the outer portions of the notch 17, which strike against the sides of the arm 6 and form stops for limiting the movement thereof.

In this manner, a frictionless mounting is 25 provided for the semaphore arm, and the arm is also locked in position. The notch in the actuating arm 6 is eliminated so that the arm may be bent to the proper form in a gauge before the device is assembled, and is 30 not easily bent out of the proper shape. The assembling is greatly simplified and the semaphore arm does not rub on the surface of the actuating arm and thereby cause friction, especially when the device is in a tilted 35 position.

While but one illustrative embodiment of this invention has been shown and described, alterations and omissions may be had, without departing from the spirit of the invention, as defined in the following claims. 40

I claim:

1. In a device of the class described, a frame, a semaphore arm pivoted in the central portion of the frame, said arm having a 45 radial outwardly opening notch adjacent its pivot and a condition responsively movable arm projecting into the apex of said notch for directly moving the semaphore arm and the sides of this arm at a distance from the end engaging with the sides of the notch at a distance from the apex for limiting the movement of the semaphore arm in both directions.

2. In a device of the class described, a 50 plate having a stud, a leaf spring secured to

the plate, a semaphore arm inserted between the leaf spring and the plate and pivoted on said stud, said arm having a V-notch opening outwardly from the axis of rotation, and an actuating lever projecting into said 55 notch.

3. In a device of the class described, a plate having a stud, a leaf spring secured to the plate, a semaphore arm inserted between the leaf spring and the plate and pivoted 60 on said stud, said arm having a V-notch with the apex of the notch near the axis of rotation, and an actuating lever projecting into said notch with the end engaging the arm at the apex of the notch. 70

4. In a device of the class described, a plate having a stud, a leaf spring secured to the plate, a semaphore arm having an aperture, said semaphore arm inserted between the leaf spring and the plate with the stud 75 entered in said aperture, a condition responsively movable arm to directly engage and move the semaphore arm, and means for locking the leaf spring after the semaphore arm has been inserted to prevent said 80 arm from being displaced.

5. In a device of the class described, a plate having a stud and an aperture, a leaf spring anchored to the plate, a semaphore arm having an aperture, said semaphore arm inserted between the leaf spring and the plate with the stud entered in said aperture in the arm, a condition responsively movable arm to directly engage and move the semaphore 85 arm and a tongue formed on the leaf spring 90 adapted to be inserted through the aperture in the plate and bent over after the semaphore arm is inserted to lock the arm on the stud. 95

6. In a semaphore indicator, a frame, an indicator pivoted in the central portion of the frame having a notch opening outwardly from adjacent the pivot thereof, and a condition responsively movable arm engaging at its end in the notch close to the pivot 100 for moving the indicator in opposite directions and the sides of the arm at a distance from the said end engaging the sides of the notch at the outer portions thereof for limiting the movement of the indicator in both 105 directions.

Signed at Chicago this 10th day of November, 1926.

WILLIAM P. DALRYMPLE.
